US0D1005857S

(12) **United States Design Patent** (10) Patent No.: **US D1,005,857 S**
(45) Date of Patent: ** Nov. 28, 2023

(54) **DEVICE FOR MEASURING MOISTURE IN MOUTH**

(71) Applicant: **Murata Manufacturing Co., Ltd.**, Nagaokakyo (JP)

(72) Inventors: **Tomoki Takahashi**, Nagaokakyo (JP); **Jun Tagagi**, Nagaokakyo (JP); **Hiroaki Togashi**, Nagaokakyo (JP); **So Noguchi**, Hirakata (JP); **Kinue Katayama**, Moriguchi (JP)

(73) Assignee: **Murata Manufacturing Co., Ltd.**, Nagaokakyo (JP)

(**) Term: **15 Years**

(21) Appl. No.: **29/770,756**

(22) Filed: **Feb. 16, 2021**

(30) **Foreign Application Priority Data**

Aug. 31, 2020 (JP) ..... 2020-018401 D

(51) LOC (14) Cl. **10-05**

(52) U.S. Cl.

USPC **D10/56**; D24/152

(58) **Field of Classification Search**

(57) **CLAIM**

The ornamental design for a device for measuring moisture in mouth, as shown and described.

DESCRIPTION

1st embodiment:

FIG. 1: Perspective view

FIG. 2: Perspective view

FIG. 3: Perspective view

FIG. 4: Front view

FIG. 5: Rear view

FIG. 6: Top view

FIG. 7: Bottom view

FIG. 8: Right view

FIG. 9: Left view

FIG. 10: Partial enlarged view of FIG. 5

FIG. 11: Partial enlarged view of FIG. 7

FIG. 12: Another perspective view, wherein its arm portion is slightly bent

FIG. 13: Another perspective view, wherein its arm portion is slightly bent

FIG. 14: Another bottom view, wherein its arm portion is slightly bent

2nd embodiment:

FIG. 15: Perspective view

FIG. 16: Perspective view

FIG. 17: Perspective view

FIG. 18: Front view

FIG. 19: Rear view

FIG. 20: Top view

FIG. 21: Bottom view

FIG. 22: Right view

(Continued)

FIG. 23: Left view

FIG. 24: Partial enlarged view of FIG. 19

FIG. 25: Partial enlarged view of FIG. 21

FIG. 26: Another perspective view, wherein its arm portion is slightly bent

FIG. 27: Another perspective view, wherein its arm portion is slightly bent

FIG. 28: Another bottom view, wherein its arm portion is slightly bent

3rd embodiment:

FIG. 29: Perspective view

FIG. 30: Perspective view

FIG. 31: Perspective view

FIG. 32: Front view

FIG. 33: Rear view

FIG. 34: Top view

FIG. 35: Bottom view

FIG. 36: Right view

FIG. 37: Left view

FIG. 38: Partial enlarged view of FIG. 33

FIG. 39: Partial enlarged view of FIG. 35

FIG. 40: Another perspective view, wherein its arm portion is slightly bent

FIG. 41: Another perspective view, wherein its arm portion is slightly bent

FIG. 42: Another bottom view, wherein its arm portion is slightly bent

4th embodiment:

FIG. 43: Perspective view

FIG. 44: Perspective view

FIG. 45: Perspective view

FIG. 46: Front view

FIG. 47: Rear view

FIG. 48: Top view

FIG. 49: Bottom view

FIG. 50: Right view

FIG. 51: Left view

FIG. 52: Partial enlarged view of FIG. 47

FIG. 53: Partial enlarged view of FIG. 49

FIG. 54: Another perspective view, wherein its arm portion is slightly bent

FIG. 55: Another perspective view, wherein its arm portion is slightly bent

5th embodiment:

FIG. 56: Another bottom view, wherein its arm portion is slightly bent

FIG. 57: Perspective view

FIG. 58: Perspective view

FIG. 59: Perspective view

FIG. 60: Front view

FIG. 61: Rear view

FIG. 62: Top view

FIG. 63: Bottom view

FIG. 64: Right view

FIG. 65: Left view

FIG. 66: Partial enlarged view of FIG. 61

FIG. 67: Partial enlarged view of FIG. 63

FIG. 68: Another perspective view, wherein its arm portion is slightly bent

FIG. 69: Another perspective view, wherein its arm portion is slightly bent; and,

FIG. 70: Another bottom view, wherein its arm portion is slightly bent.

The broken lines depict portions of the device for measuring moisture in mouth that form no part of the claimed design. The dot dash broken line rectangles depict the limits of the enlarged views and form no part of the claimed design.
